SPARKING PLUG

Charles Molyneux Carington and Archibald Edward Postlethwaite, London, England, assignors to K. L. G. Sparking Plugs Limited, London, England, a British company

Application July 7, 1937, Serial No. 152,294
In Great Britain December 5, 1936

10 Claims. (Cl. 123—119)

This invention is for improvements in sparking-plugs, for internal-combustion engines, of the kind in which the earthed electrode, which is carried by the body of the plug, is constituted by one or more fine wires; a sparking-plug of this kind is described in British patent specification No. 448,913.

The attachment of the wires to the body of the plug has hitherto presented serious manufacturing difficulties. For example, it is commercially impracticable to drill holes of, say, .02 inch diameter in the plug-body owing to the frequent breakage of the drill bits. The object of this invention is to provide an inexpensive mounting for the fine wires.

According to the present invention, the plug-body comprises two interengaging parts, and each wire is located by a groove in one part; preferably each groove is closed by the other part. 20 The said grooves are preferably formed in the said part prior to the fitting of the parts together, and the width of each groove is preferably slightly less than the diameter of the wire, so that the wire is gripped in addition to being located, 25 by the groove.

The part of the body which is formed with the grooves may be a small metal ring which, when the wires have been inserted in the grooves, is placed on a shoulder in the plug-body which 30 closes the grooves. The ring may be held in place by any suitable means.

Where the wires are disposed substantially radially with respect to the plug axis, they are located against movement radially outwards by 35 their abutment against the inner wall of the plug-body surrounding the ring; in order to locate them against movement in the other direction each groove may be formed with a local enlargement at a part of its length other than its innermost end so that the diameter of the wire at this part is uncompressed, or is compressed to a less extent than the remainder, when the wire is forced into the groove. For example, the groove 40 may be discontinued at a point near its outer end so that the wire at this point is undeformed and thus provides a head.

A specific embodiment of the present invention will now be described by way of example with reference to the accompanying drawing of which:

Figure 1 is a plan view of the small metal ring into which the wires are affixed.

Figure 2 is a sectional elevation on the line 2—2 of Figure 1.

Figure 3 is a diagram illustrating the method

of inserting the wires into the grooves of the ring, Figure 4 being a sectional elevation to an enlarged scale on the line 4—4 of Figure 3 and Figure 5 a plan view, to the same enlarged scale, of the wire and the part of the ring shown in Figure 4, and

Figure 6 is a sectional elevation of the assembled sparking-plug body.

As shown first in Figures 1 and 2, a steel ring 10 is milled on one face with six radial grooves 11 of substantially square cross-section. The outer edge of the grooved face of the ring is chamfered as shown at 12 and the inner edge of the other face is chamfered at 13. The purpose of these chamfers is explained below.

When the wires are to be inserted into the grooves, the ring 10 is placed on an anvil 14 having a locating ledge 15 and a central cylindrical mandrel 16. The wires 17 are brought in from six supply spools until their ends abut against the mandrel 16 and they are then pressed lightly into the grooves 11. A tubular tool 18 is now brought down on to the wires whereby they are pressed tightly into the grooves. An outer tool 19 slidable on the tube 18 is now pressed down 25 so as to shear off the wires flush with the outer wall of the ring 10.

The diameter of each wire is slightly greater than the corresponding dimension of the groove 11. For example, the diameter of the wire may 30 be .02 inch and each groove 11 may be .018 inch in breadth and .018 inch in depth. Consequently when the wires are forced into the grooves, the part of each wire which engages the groove is deformed into an approximately square shape as 35 shown in Figure 4.

The friction between this deformed portion and the groove is sufficient to retain the wire in position until the final assembly of the sparking-plug. The outer end of the wire, however, at the region of the chamfered edge 12 of the ring is unconstrained in a direction laterally of the groove so that at this region an enlarged head 20 is formed as shown in Figure 5 and in broken lines in Figure 4. This head is of larger transverse dimensions than the groove and therefore prevents movement of the wire in a direction towards the centre of the ring 10. The chamfer constitutes, in effect, a local enlargement in the groove 11 at the outer end of the groove. But 40 such enlargement could be provided at any other part of the groove except at the innermost end thereof.

The pressure applied by the tool 18 may be such as to leave the wires standing very slight-

ly above of the ring 10 as shown in Figure 4. As shown in Figure 6, the sparking-plug body 21 is formed near the mouth with an inwardly-directed shoulder 22. The ring with the wires 5 in position is removed from the anvil 14, turned upsidedown, and placed with the wires downwards on the shoulder 22. The ring 10 and the shoulder 22 thus constitute the two "interengaging parts" referred to above and in the claims. 10 The upstanding wall 23 of the plug-body is now rolled down on to the ring 10 so as to clamp it tightly in position. In Figure 6 the wall 23 is shown on the left-hand side as it appears before the rolling operation and on the right-hand side 15 as it appears after the rolling operation. The protrusion of each wire by a very small distance beyond the face of the ring ensures that, when the plug is finally assembled as above described, the wires are firmly clamped between the ring 20 and the shoulder 22.

In the assembled plug it will be seen that the wires 17, the inner ends of which have been accurately positioned by their abutment against the mandrel 16, are prevented from moving radially outwards by the abutment of their outer ends 25 against the wall of the plug-body. They are prevented from moving radially inwards by the enlarged heads described above with reference to Figures 4 and 5. Movement in any other direction is rendered impossible by the walls of the 30 grooves and by the gripping action of the ring 10 and the shoulder 22.

The purpose of the inner chamfer 13 is to provide with the rolled-over wall 23 of the body, 35 a smooth entrance mouth to the plug, as shown on the right-hand side of Figure 6.

It will be understood that any desired number of wires may be used and that they need not be arranged radially. For example, each wire 40 may pass continuously from one groove to another in either a straight or suitably curved path. The metal for the wire may be platinum, iridium, or platinum-iridium alloy.

We claim—

- 45 1. A sparking-plug comprising a plug-body composed of two inter-engaging parts, one of which is grooved, and an electrode comprising at least one fine wire located in said groove.
2. A sparking-plug comprising a plug-body composed of two interengaging parts, one of

50

which is formed with a plurality of grooves which are closed by the other part, and electrode means comprising a plurality of fine wires located by said grooves.

3. A sparking-plug comprising a body formed in two parts, one of which is formed with grooves prior to assembly of the plug, said grooves being closed by the other part, and electrode means comprising a plurality of fine wires located by said grooves. 5

10 4. A sparking-plug according to claim 3 wherein the width of each groove is such as to grip the wire within it.

15 5. A sparking-plug comprising a body, a metal ring adapted to engage the body and formed on one face with a plurality of radial grooves, a shoulder on the body against which the ring abuts, so that the grooves are closed by the shoulder, and electrode means comprising fine wires located by said grooves. 20

25 6. A sparking-plug comprising a body having a shoulder, a metal ring adapted to rest against said shoulder and formed with grooves which are closed by said shoulder, a rolled-over projection on the body to locate said ring in position, and electrode means comprising fine wires located by said grooves and said shoulder.

30 7. A sparking-plug according to claim 6 wherein each said groove is formed with a local enlargement at a part of its length other than its innermost end.

8. A sparking-plug according to claim 6 wherein each said groove is discontinued at a point near its outer end.

35 9. A sparking-plug according to claim 6 wherein the grooved face of the ring is chamfered at its outer edge.

40 10. A sparking-plug comprising a plug-body having a shouldered recess, a flat ring adapted to rest on the said shoulder and formed on the face which abuts said shoulder with a chamfer at its outer edge and with radial grooves of rectangular cross-section, platinum wires adapted to engage the grooves in such manner as partially to protrude beyond the grooved face of the ring, and means for pressing the ring towards the shoulder whereby the said wires are clamped between the ring and the shoulder. 45
